(57) **CLAIM**

The ornamental design for a large format printer, as shown and described.

DESCRIPTION

FIG. 1 is a right, front perspective view of a large format printer showing our new design;

FIG. 2 is a left, front perspective view of the printer of FIG. 1;

FIG. 3 is a front elevation view of the printer of FIG. 1; FIG. 4 is a right side elevation view of the printer of FIG. 1; FIG. 5 is a left side elevation view of the printer of FIG. 1; and,

FIG. 6 is a top plan view of the printer of FIG. 1. The broken lines and dotted lines depict environmental portions of the large format printer that form no part of the claimed design.
